UNITED STATES PATENT OFFICE.

JOHN C. RINGE, OF STRATFORD, CONNECTICUT, ASSIGNOR TO THE SINGER MANUFACTURING COMPANY, A CORPORATION OF NEW JERSEY.

SEWING MACHINE.

Application filed July 8, 1919. Serial No. 309,378.

To all whom it may concern:

Be it known that I, JOHN C. RINGE, a citizen of the United States, residing at Stratford, in the county of Fairfield and 5 State of Connecticut, have invented certain new and useful Improvements in Sewing Machines, of which the following is a specification, reference being had therein to the accompanying drawings.

10 This invention relates to improvements in sewing machines and in its present embodiment relates more particularly to improvements in sewing machine ruffling mechanisms.

15 The primary object of the present invention is to provide a simple but effective mechanism whereby the action and inaction of an actuated member may be controlled during the operation of the machine.

20 Another object of this invention is to provide effective means for at will controlling the operative and inoperative positions of the actuated member.

In the present embodiment of the invention, the actuated member comprises a ruffling or gathering blade carried by a vibratory-arm adapted to be actuated by a rock-shaft suitably journaled in the machine frame. Interposed between the rock-shaft 25 and a rotary driving shaft is a pivotally supported lever provided with a segmental guideway sustaining a slide-block, linked to a crank-arm on said rock-shaft and the position of which slide-block may be controlled 30 at will during the operation of the machine to vary the extent of movement of the actuated member. At a point substantially co-axial with the fulcrum of the lever, one side of the segmental guideway is cut away so 35 that by special means provided for the purpose the slide-block may be swung out of alignment with the curved path of said guideway, thereby rendering the actuated member inoperative. By this movement of 40 the slide-block an additional throw is imparted to the rock-shaft, causing the retraction of the actuated member from operative position and also causing the actuated member to be displaced relatively to the vibratory arm into a non-interfering position 45 with respect to a different operation upon the work.

The invention will be understood by reference to the accompanying drawings, in which

Fig. 1 is a rear side elevation of a sewing machine illustrating an embodiment of the present invention with the needle and presser-foot omitted and with the actuated member in its retracted inoperative position. Fig. 2 is a front end elevation of the machine with the parts in the position occupied in Fig. 1. Fig. 3 is a rear end elevation of the machine and partly in section, but with the actuated member in operative position and including the needle and presser-foot. Fig. 4 is a detail view of the controlling mechanism for the slide-block in the position illustrated in Figs. 1 and 2.

Referring to the drawings, the present invention is embodied in a sewing machine comprising a bed-plate 1 from which rises the hollow standard 2, sustaining the overhanging bracket-arm 3, terminating in the head 4. Journaled in suitable bearings provided in the overhanging arm is the main or driving shaft 5, carrying at one end the belt-wheel 6 and at its opposite end connected in the usual manner (not shown) with the needle-bar 7 carrying the needle 8. Suitably journaled for vertical reciprocation in the head 4 is the presser-bar 9 carrying the presser-foot 10 adapted to be lifted out of contact with the work by means of the usual hand lifter-lever 11 or the treadle-actuated rock-lever 12. Any well known form of stitch-forming mechanism supplemental to the needle 8 may be employed and is for that reason not illustrated in the drawings.

Referring now more particularly to the present invention, an actuated member 13, in the present instance in the form of a ruffling-blade, is secure as by screws 14 to a lateral arm of a ruffling-blade carrier 15. The carrier 15 is pivotally sustained by means of a screw 16 upon a vibratory-arm 17 and is provided with a stop-member 18 curved about one edge of and adapted to engage a pin 19 upon said vibratory arm 17 to limit the movement of the actuated member in one direction. The ruffling-blade carrier 15 is further provided with a pin 20 embraced by a fork on one end of a lever 21, pivotally supported upon the vibratory-arm 17 by means of a pivot-screw 22 and of which the other end enters a controlling notch 23 formed in a stationary bracket 24 suitably secured to the head 4 of the over-

hanging bracket-arm. A spring 21' connected at opposite ends to the lever 21 and bracket 24 acts to maintain the effective end of the actuated member 13 during its operation in engagement with the work. A bridge-plate 25 secured by screws, as 26, upon the bracket 24 provides a guideway for the vibratory-arm 17 which is pivotally suspended from the head 4 by means of a pivot-screw 27.

The vibratory arm 17 is connected by means of a link 28 with a lateral arm 29 upon a rock-shaft 30 journaled at its opposite ends in suitable bearings provided in brackets 31 and 32 secured to the rear side of the overhanging arm. Adjacent to the bracket 32, the rock-shaft 30 is provided with a lateral arm 33 pivotally connected with one end of a link 34 of which the opposite end is connected in a like manner and by means of a pivot-screw 34' with a slide-block 35 having a forwardly projecting finger 35'. The slide-block 35 is slidably adjustable in a segmental guideway 36, provided in a vibratory segment-lever 37 fulcrumed intermediate its ends upon a bracket 38 projecting from the overhanging bracket-arm 3. The segment-lever 37 is vibrated by means of a pitman 39 having a strap embracing an eccentric 40 upon the main- or actuating-shaft 5. From the foregoing it will be seen that the member 13 may be actuated to ruffle material passed to the stitch-forming mechanism, and that said movements of the actuated member 13 are dependent upon the position of the slide-block 35 in the guideway 36. The extreme movement in one direction of the slide-block in the guideway is preferably limited by an adjustable stop-block 41, so formed as to provide clearance for the finger 35' and locked in position by the thumb-nut 42.

It is however desirable to at times throw the actuated member 13 out of operation during the operation of the machine and at the same time, throw the actuated member out of operative position so as not to interfere with intermediate operations. The present invention provides a simple solution for this problem and accomplishes both of these results by means acting through said operative connections in the manner about to be described.

The link 34 is formed intermediate its ends with an apertured ear 43 pivotally bolted to one arm 44' of a two-armed controlling lever 44 in turn pivoted by means of a pivot-screw 45 to the free end of a crank-arm 46 upon a treadle-actuated rock-shaft 47. The rock-shaft 47 is journaled in bearings provided in spaced lugs, as 48, upon the bracket 32. A coiled spring 50 surrounding the shaft 47 and of which one end enters an aperture in the collar 51 fast upon said shaft and of which the other end

bears against one of the lugs 48 normally tends to turn the shaft 47 clockwise in the illustration of Fig. 2 and to an extent limited by a stop-screw 52 threaded into the lug 48 and bearing against a shoulder 53 provided on the hub of the crank-arm 46. To turn the shaft 47 against the action of the coiled spring 50, a peripherally grooved segment 54 is suitably secured upon the shaft and is adapted to be connected with a treadle (not shown) by means of a chain 55 secured by a screw 56 to the segment and overlying the peripheral groove thereof.

When it is desired to maintain the rock-shaft 47 in any given position and relieve the operator from the effort of maintaining it in said position, a clamp-screw 57 threaded into the lug 48 is adapted to be caused to engage the shaft and lock the same against movement by the spring 50, a spring-plate 58 suitably secured to said lug acting to prevent the clamp-screw 57 from loosening under the vibration of the machine.

When the spring 50 is permitted to rock the shaft 47, the slide-block is retracted in the direction of the axis of the segment-lever 37, the throw of the rock-shaft 30 thus gradually approaching zero. At this point, the lower rib 59 of the guideway in the segment lever is cut away so that as the slide-block passes the axis of said segment-lever or in other words the zero position, the end of the slide-block opposite the finger 35' may be displaced out of alignment with the arcuate path of the guideway 36, the finger 35' however remaining in engagement with the upper portion of the guideway. Positive means are provided to cause this displacement of the slide-block by the provision on an arm 44' of the two armed lever 44 of an adjustable screw-stud 60 adapted to engage the head 61 of a screw threaded into the machine frame.

In the operation of the present machine, when it is desired to ruffle the fabric the operator actuates the treadle until the slide-block 35 enters the guideway 36 to an extent determined by the amount of ruffling desired. During an extended period of ruffling with a certain degree of fullness, the operator may clamp the shaft 47 by means of clamp-screw 57. When it is desired to throw the ruffling blade or actuated member 13 out of operation during the operation of the machine, the shaft 47 is released to permit the spring 50 to retract the same in a counter-clockwise direction in Fig. 3 of the drawings. This movement of the rock-shaft and consequently of the crank-arm 46 thereof, causes the two-armed lever 44 to act on the link 34 and retract the slide-block 35 toward the axis of the segment lever 37 thereby throwing the actuated member 13 out of operation. When the slide-block reaches the opening in the guideway 36, the screw-stud 60 engages the

screw-head 61, thereby preventing the continued movement of the slide-block in its arcuate path. The crank-arm 46 however has not reached its stopping position determined by the stop-screw 52 and shoulder 53; and consequently the screw-stud 60 slides downwardly along the screw-head 61 forcing the pivotal point of the slide-block 35 downwardly and thereby rocking shaft 30 in a clockwise direction when viewed as in Fig. 3. This movement of the rock-shaft beyond its normal range causes the vibratory-arm 17 to swing away from the needle, carrying the actuated member 13 therewith.

15 At the same time, the engagement of the upper end of lever 21 with a wall of the notch 23 swings the operative end of the member 13 above the work and out of the way. The separator-blade and work-guides 20 usually employed in this class of machines are omitted from the drawings to better illustrate the mechanism and in view of the fact that they are well known in the art and form no part of the present invention.

25 It will be observed that upon the downward movement described of the pivotal point of the slide-block 35 that the rearward end tilts downwardly due to its greater weight, causing the finger 35' to remain 30 in engagement with the guideway and thereby insure re-entrance of the slide-block into the guideway when it is desired to again commence a ruffling operation.

From the foregoing, it will be observed 35 that the controlling mechanism of the actuated member 13 not only determines the action and inaction of said actuated member and its operative position in action, but also determines its inoperative position beyond its normal range of movement and transmits these several movements to the actuated member through the connections for causing the same to operate upon the work.

45 Having thus set forth the nature of the invention, what I claim herein is—

1. In a ruffling mechanism for sewing machines, in combination, a driving shaft, a ruffling-blade, connections between the driving shaft and said ruffling-blade for imparting operative movements to the latter, and treadle controlled means constructed and arranged to impart to said ruffling-blade during the operation of the machine a movement of greater amplitude than the normal range to throw said ruffling-blade into an inoperative position in alinement with but beyond its normal path of operating movement.

50 60 2. In a ruffling mechanism for sewing machines, in combination, a driving shaft, a ruffling-blade normally having a limited path of operative movement, operative connections between the driving shaft and the ruffling-blade including a vibratory lever, a

slide-block shiftable upon said lever for varying the extent of movement of the ruffling-blade within said limited path, and means constructed and arranged whereupon the shifting of said slide-block in one direction imparts to the ruffling-blade an increased amplitude of movement into inoperative position, through a path in alinement with but beyond the normal range of operative movement of the ruffling-blade. 70

3. In a ruffling mechanism for sewing machines, in combination, a driving shaft, a ruffling-blade capable of being thrown into and out of operation and out of operative position during the operation of the machine, connections between the driving shaft and the ruffling-blade for imparting operative movements to the latter, means constructed and arranged for imparting to said ruffling-blade an amplitude of movement greater than the normal range to throw said ruffling-blade into an inoperative position in alinement with but beyond its normal path of operative movement, and means for automatically tilting the ruffling-blade out of contact with the work by its movement into inoperative position. 80

4. In a ruffling mechanism for sewing machines, in combination, a rotary actuating shaft, a ruffling-blade, operative connections intermediate the actuating shaft and said ruffling-blade including a longitudinally immovable rock-shaft, a journal for said rock-shaft, means under the control of the operator during the operation of the machine for throwing the rock-shaft into and out of operation, and means for increasing the final movement of said rock-shaft before it is rendered ineffective to retract said ruffling-blade in a path in alinement with but beyond its normal path of operative movement. 90

5. In a ruffling mechanism for sewing machines, in combination, a vibratory arm, a ruffling-blade sustained by said vibratory arm, means for vibrating said arm to impart operative movements to the ruffling-blade, treadle controlled means whereby said arm may be retracted during the operation of the machine in a path in alinement with but beyond the normal range of operative movement and rendered inoperative, and means for automatically displacing the ruffling-blade relatively to the vibratory arm during said retracting movement into inoperative position. 100

6. In a ruffling mechanism for sewing machines, in combination, a vibratory arm, a ruffling-blade, a pivotal support for said ruffling-blade upon said vibratory arm, means for vibrating said arm to impart operative movements to the ruffling-blade, treadle controlled means whereby said arm may be retracted during the operation of the machine in a path in alinement with but beyond its normal range of operative move- 110 115 120 125 130

ment and rendered inoperative, means for yieldingly urging said ruffling-blade in one direction upon its pivotal support during the normal operation of the vibratory arm, and means for automatically retracting the ruffling-blade upon its pivotal support in the opposite direction as said vibratory arm is rendered inactive.

7. In a ruffling mechanism for sewing machines, in combination, a ruffling element, an actuating shaft, operative connections intermediate said actuating shaft and said ruffling element including a vibratory lever, a slide-block shiftable upon said lever in an arcuate path, and means constructed and arranged to retract said slide-block from said vibratory lever in a direction substantially transverse to said arcuate path to shift said ruffling-element into inoperative position.

10 8. In a ruffling mechanism for sewing machines, in combination, an actuating shaft, a ruffling-element, operative connections intermediate the actuating shaft and the ruffling-element including a vibratory segment lever, a slide-block shiftable in an arcuate path upon said segment lever, a rock-shaft, a crank-arm upon said rock-shaft, a link interposed between the crank-arm and said slide-block, and means for shifting said slide-block upon said segment lever in an arcuate path to render said ruffling-element inoperative, said last named means acting to displace said slide-block when retracted, out of alinement with said 35 arcuate path.

40 9. In a sewing machine, in combination, a rotary actuating shaft, a ruffling-element, operative connections intermediate the actuating shaft and said ruffling-element including a vibratory segment lever, a slide-block shiftable in an arcuate path upon said segment lever, a rock-shaft, a crank-arm upon said rock-shaft, a link interposed between the crank-arm and said slide-block, 45 means for shifting the slide-block upon said lever into retracted position, and means whereby a shifting of said slide-block imparts endwise movement to said link beyond its normal path of operative move-

ment to thereby retract said ruffling element 50 into inoperative position.

10. In a ruffling mechanism for sewing machines, in combination, an actuating shaft, a ruffling-element, operative connections intermediate said actuating shaft and the ruffling-element including a vibratory segment lever, a slide-block shiftable in an arcuate path upon said lever, means for yieldingly holding said slide-block in retracted position out of alinement with said 60 arcuate path, means whereby the position of said slide-block upon said lever may be controlled against the action of said yielding means, and means whereby said slide-block remains in ineffective contact with 65 said segment lever intermediate the axis of vibration of said lever and the extreme retracted position of said slide-block.

11. In a ruffling mechanism for sewing machines, in combination, an actuating 70 shaft, a ruffling element, operative connections intermediate said actuating shaft and the ruffling-element including a vibratory lever, a slide-block shiftable upon said lever in an arcuate path, means constructed and 75 arranged whereby at a predetermined point in said arcuate path the slide-block is shifted from said arcuate path in a direction substantially transverse thereto to throw said ruffling-blade into inoperative position, 80 and means permitting adjustment of the point in said path where said slide-block is transversely shifted.

12. In a ruffling mechanism for sewing machines, in combination, an actuating 85 shaft, a ruffling blade, operative connections intermediate said actuating shaft and said ruffling-blade including a vibratory lever, a slide-block shiftable in an arcuate path upon said lever, and means for limiting the movement of the slide-block in said 90 arcuate path in one direction, said last named means acting to bodily displace said slide-block out of alinement with said arcuate path.

In testimony whereof, I have signed my name to this specification.

JOHN C. RINGE.
